(57) **CLAIM**

The ornamental design for a vehicle hood, as shown and described.

DESCRIPTION

FIG. 1 is a top, front and right side perspective view of a vehicle hood showing our new design;

FIG. 2 is a bottom and right side perspective view thereof; FIG. 3 is a bottom, front and right side perspective view thereof;

FIG. 4 is a top, rear, and left side perspective view thereof;

FIG. 5 is a front view thereof.

FIG. 6 is a rear view thereof.

FIG. 7 is a top view thereof; and,

FIG. 8 is another top view of the vehicle hood shown in FIG. 1, with the vehicle hood shown mounted on a vehicle that is depicted in de-emphasized and halftone portions so as to illustrate the environmental structure for the vehicle. These portions form no part of the claimed invention. More particularly, in FIG. 8, the vehicle hood of the present invention is shown within the broken lines, and any elements shown outside of the broken lines form no part of the claimed invention, but are instead included to show environmental aspects thereof.
